SEALING APPARATUS

Arthur J. White, Cleveland Heights, and Anthony J. Marshaus, East Cleveland, Ohio, assignors to General Electric Company, a corporation of New York

Application September 22, 1939, Serial No. 296,064

8 Claims. (Cl. 49—2)

Our invention relates to apparatus for sealing vitreous bodies together and more particularly to apparatus for sealing the stems of incandescent and arc lamps and other electrical devices to the enclosing bulb or envelope.

According to the method disclosed in application Serial No. 176,910, A. J. White, filed November 27, 1937, two vitreous bodies such as a stem and an envelope for an enclosed arc lamp can be sealed together by the heat generated by induction in a conductive body located adjacent and preferably in contact with one of the vitreous bodies. The principal object of our invention is to provide apparatus for sealing two vitreous bodies together in this manner.

Another object of our invention is to provide apparatus for automatically positioning the vitreous bodies in sealing relation and manipulating and timing automatically all operations in the sealing process.

Another object of our invention is to provide apparatus for sealing the electrode supporting stems in both ends of the vitreous tube forming the enclosure or envelope for an arc lamp.

Other objects and advantages of our invention will be apparent from the following detailed description of a species thereof and from the accompanying drawings.

In the drawings, Fig. 1 is a plan view of a sealing apparatus comprising our invention with some of the heads thereof only outlined and others broken away to show the underlying parts; Fig. 2 is a vertical section through the turret along line 2—2 of Fig. 1 with the adjacent head shown in elevation; Fig. 3 is a perspective view of the cage for supporting the stem and the end of the vitreous envelope to be sealed thereto; Fig. 4 is a front elevation of the gripping jaws of the head; and Fig. 5 is a diagrammatic perspective view of the operating and repositioning means for the push down apparatus and induction coils respectively.

The sealing apparatus shown in Fig. 1 is comprised of sixteen heads 10 mounted about the periphery of the turret 11 which is indexed in a counter-clockwise direction in a manner to advance each of the heads 10 into each of the stations indicated in turn. An operator stands before stations A and B and, in the interval the heads 10 are at these stations, inserts a stem in cage 12 (Figs. 1 and 2) and the tubular vitreous envelope 13 in between the jaws 14 and 15. As shown in Fig. 3, the stem 16 comprises a flared stem tube 17 sealed to one end of the exhaust tube 18 and about portions of the leading-in wires 19 55

and 20 and the operation of inserting said stem 16 in the machine consists in threading the lower ends of the exhaust tube 18 and the leading-in wires 19 and 20 through the center opening in the holder 21 and resting the flange 22 of the stem tube 17 on the ring-shaped heating element 23 carried thereby. An upwardly projecting button 24 on the holder 21 serves to locate the stem 16 and to provide protection for the leading-in wires 19 and 20 at this point. The holder 21 is made of a non-magnetic and non-conductive material such as asbestos or sillimanite whereas the heating element 23, which rests in a similarly shaped circular groove therein, is made of a conductive material which does not stick to the vitreous stem 16, such as carbon. The heating element 23 fits loosely in the holder 21 and can be lifted out and replaced as often as desired. As there is some danger of the exhaust tube 18 being struck and broken off during the operation of the sealing apparatus, the lower end thereof enters a central aperture in the non-conductive guard 25 which is mounted on continuations of the metal side rods 26 on which the holder 21 is mounted. The side rods 26 and the plate 27 from which they extend are, in this instance, of brass. The metal bracket 28 attached to the turret 11 by the nut 29 supports the cage assembly 12.

The insertion of the tubular envelope or bulb 13 takes place after the operator opens or separates the jaws 14 and 15 by swinging the lever 30 to one side. The jaws 14 and 15 are pivoted on separate rods 31 extending downward from bracket 32 and are normally held in a closed position by the wedge 33 which takes a position between the rollers 34 on rearwardly extending portions thereof. When said jaws 14 and 15 are opened, the wedge 33 is withdrawn from between said rollers 34 by the lever 35 which is connected to the manually actuated lever 30 through the link 36 and a spring 37 extending between posts in the rearwardly extending portions of said jaws 14 and 15 separates said jaws. The lever 35 engages the wedge 33 through a pin 38 entering a slot in the lever 35 and causes the jaws 14 and 15 to close when manual pressure is taken from the lever 30 as the contracting force of the spring 39 then pulls it out of position. The spring 39 extends between posts in the lever 35 and the bracket 32 which also provides guide ways on top of the jaws 14 and 15 for the wedge 33. Jaw 14 engages the tubular envelope or bulb 13 at two different points through the V-notched plates 40 whereas jaw 15 engages said envelope or bulb 13 through the rubber insert 41 which prevents it

from being moved longitudinally while gripped thereby.

When the envelope 13 is inserted in the jaws 14 and 15, the rim of the opening in the lower end is rested on the flange 22 of the stem 16 as shown in Fig. 3 and said jaws are at a height determined by the position of the rods 31 which support the collars 42 on which the said jaws rest. The rods 31 are mounted in vertical openings in the stationary bracket 43 fastened to the standard 44 extending upward from the bracket 28 and are positioned vertically by the yoke 45 on the lower ends thereof. At this time, the pressure of expansion of the spring 46 within the upper end of the standard 44 turns the lever 47 which engages the pin 48 held by the yoke 45 so that said yoke 45 is kept against the bracket 43. The lever 47 pivots on the pin 49 held by bracket 43 and is permitted to swing to this position only as the pawl 50 is tripped between unloading and reloading of the envelope or bulb 13. The tripping is done by the screw on the end of the bar 51 which extends downward between the jaws 14 and 15 from the wedge 33 and backward through an opening in the standard 44 and which is moved back against the pawl 50 by the greater closing movement of jaws 14 and 15 when the envelope or bulb 13 is not therebetween.

The next succeeding stations taken by the head 10 are idle ones and it is not until stations E and F are reached that electrical energy is introduced in the ring-shaped heating elements 23 carried by the cages 12. At these stations, two hollow coils 52' and 52 connected to a source of high frequency electricity are moved up about the cages 12 so as to induce a relatively high current in the heating elements, sufficient to cause the outer portion of the flange 22 of the stem 16 and the lower portion of the rim of the bulb 13 to be fused and sealed together. In some instances, the outer portion of the flange 22 is melted down at station E and it becomes desirable for the bulb 13 to be pushed down thereagainst again at this station; otherwise the bulb 13 is not moved down until station F is reached. Whether the bulb 13 is moved vertically depends on the adjustment of the bulb shifting means which consists of the cross arm 53 mounted on the upper end of a vertical rod 54 passing through the center of the machine and means held thereby which engages and raises the inner end of the levers 47 of the heads 10. The end of the arm 53 adjacent the heads 10 at stations E and F carries an angular bracket 55 on which is mounted the guides 56 for the push pins 57 and an upward movement of the arm 53 carries said pins 57 against the screws 58 in the end of the levers 47. The push pins 57 rest on springs 59 within the guides 56 which limit the pressure with which the bulbs 13 are pressed down onto the flares 16. The compression force under which the spring 59 is held is established by the distance the adjusting screw 60 is screwed in or out of the guide 56. If no vertical adjustment of the bulb 13 is desired at station E, the screw 60 or guide 56 can be lowered so that the push pin 57 does not engage the screw 58. Once the lever 47 and bulb 13 are moved, there is no further use for the shifting means as the pawl 50 which is pivotally mounted on said lever 47 at 61 is pressed against the teeth of the insert 62 by the spring 63 and is held in place thereby.

The cross arm 53 of the shifting means is moved vertically in proper time relation to the

other operations of the machine in the same manner as the induction coils 52' and 52 by cam means on the single drive shaft 64 shown in Fig. 5. The drive shaft 64 is mounted below the turret 11 in the frame (not shown) of the machine and is the means for actuating the indexing means (also not shown) for the turret 11. The rod 54 on which the cross arm 53 is mounted extends downward through the hollow column 65 supporting the turret 11 and connecting it to the indexing means and is actuated from the cam 66 through the lever system comprising levers 67 and 68. Lever 67 is pivotally mounted on the frame of the machine through the bracket 69 and engages the ways of the cam 66 through a roller (not shown) whereas lever 68 is pivotally mounted on the bracket 70 extending from the frame and is connected to the lever 67 through links 71 and to rod 54 through link 72 and block 73. The actuating means for the induction coils 52' and 52 at these stations comprises the cam 14; the lever 75 which engages the said cam 14 through a roller (not shown) and the vertically disposed rod 76 which is attached to said lever 75 through the link 77 and block 78 and which extends upward through the frame and the bracket 79 thereon to the platform 80. Lever 75 turns about the pivot provided in the bracket 81 which is fastened to the frame. Both induction coils 52' and 52 are connected in series by the single piece of flattened pipe forming both coils and are attached to the platform 80 by the end portions thereof which are clamped onto the insulating plate 82 thereon.

During the intervals the head 10 is at stations E and F, the heating element 23 is increasing in temperature and during the movement of the head 10 through stations G and H some effective heat still remains therein. It is, therefore, preferred that the bulb 13 and stem 16, now as a single unit, be left in the head 10 until station J is reached. The lamps taken from the machine are first placed in an annealer which heats the sealed end and are then transferred to a rack to cool.

The function of one half of the stations of the machine has now been described and the sealing of a stem 16 over one end of the tubular envelope or bulb 13 is complete. The other half of the machine duplicates the operations performed by the first half in sealing a second stem to the opposite end of the bulb 13. To do this, the bulbs 13 are removed from the heads 10, turned end for end, and returned thereto. A considerable saving in equipment and handling is realized by this method of operation since some of the apparatus required for the first half also functions in the second half and since handling of the bulbs 13 is reduced to a minimum. The bulbs 13 and stems in this instance are inserted in the head 10 while they are at stations J and K in the same manner as these operations were performed at stations A and B; the stem first being placed on the heating element 23, thereupon the bulb 13 is reinserted in the jaws 14-15 and pushed down into engagement with the stem. As described heretofore in connection with the sealing of the first stem, the leads 19 and 20 are threaded through the central opening in the holder 21 and the stem is positioned laterally by the button 24. Between the time the bulb 13 is removed from the head 10 and returned thereto, the operator removes his hand from the release lever 30 of the jaws 14-15 so that they close and the screw on the end of bar 51 engages the pawl 50 which is withdrawn from between the teeth of the insert 61. The jaws

14-15 are then free to rise to their upper position and take a position corresponding to that held at stations A and B. Following the insertion of the stem and bulb 13 into the head 10, it is indexed in turn to station L and then to station M which are idle stations.

The heat for sealing is created in the heating elements 23 by the electrical current induced therein by the induction coils 84 and 85 at stations N and O. The induction coils 84 and 85 are mounted on insulating plate 86 on a movable platform 87 like in the prior instance but are moved in and out of operative relation to the cage 12 of the head 10 by movement of the rod 88 (Fig. 5) which is actuated from lever 89 through link 90 and block 91. Lever 89 pivots on a pin extending from the bracket 92 on the frame and engages the ways of the cam 93 through a roller not shown. For reasons of simplicity, the induction coils 84 and 85 are connected in series with the other induction coils 52' and 52 at stations E and F. The series connection is made through hollow flexible pipe 94 and the connections from the source of high frequency current 98 are made through tubular pipe 95 to one end of coil 84 and lead 96 (Fig. 2) to the end 83 of coil 52. The cooling water is introduced into the hollow interior of the pipe 95 through the rubber hose 97 and after flowing through each of the coils 84, 85, 52' and 52 passes out the coil end 83 (see Fig. 2). The bulb 13 in this instance is pushed down by means on the other end of the cross arm 53 in the same manner as at stations E and F. The period taken by the head 10 in passing through the next two stations P and Q permits the lamp seal to cool. The finished lamp is removed from the machine at station A.

What we claim as new and desire to secure by Letters Patent of the United States is:

1. Apparatus for sealing a plurality of vitreous bodies together comprising a heating element of material which is capable of being heated by induction and to which the fused vitreous bodies will not permanently adhere, said element being arranged to engage and support at least one of the vitreous bodies at the area where it is to be sealed, a holder of non-magnetic material for supporting the heating element, a supporting cage for the holder comprising rods for suspending said holder, means independent of said cage for holding a second vitreous body in sealing relation to the first-mentioned vitreous body, and an induction coil disposed in axial alignment with said cage and means for moving said coil to a position surrounding the said cage and the holder for inducing electrical currents into said heating element to heat it to a high degree so that heat is conducted therefrom to the vitreous bodies in sufficient quantity to cause the adjacent portions thereof to be fused together.

2. Apparatus for sealing a plurality of vitreous bodies together comprising a heating element of material which is capable of being heated by induction and to which the fused vitreous bodies will not permanently adhere, said element being arranged to engage and support at least one of the vitreous bodies at the area where it is to be sealed, a holder of non-magnetic material for supporting the heating element and positioning the said vitreous body thereon, a supporting cage for the holder comprising rods for suspending said holder, gripping means independent of said cage for holding a second vitreous body, an induction coil disposed in axial alignment with said cage and means for moving said coil to a posi-

tion surrounding said cage and holder for inducing electrical currents into the heating element to heat it to a high degree so that heat is conducted therefrom to the vitreous bodies in sufficient quantity to cause the adjacent portions thereof to be fused together, and means for moving said gripping means nearer the heating element for pressing the second-mentioned body against the first to compress the seal therebetween.

3. Apparatus for sealing electric lamp stems in both ends of a tubular envelope comprising an intermittently rotatable turret, a plurality of heads mounted on said turret and carried thereby through a plurality of stations, each of said heads comprising a stem support member capable of being heated by induction and arranged to hold a stem in an upright position, each of said heads further comprising an envelope holder arranged above and in alignment with said stem support member to hold an envelope in a vertical position with its lower end enclosing and engaging said stem, induction coils located at at least two heating stations in vertical alignment with the path of movement of said heads, means for moving said coils vertically in timed relation to the turret movement to and from positions surrounding stem support members temporarily located at said heating stations to heat said stem support members by induction and thereby fuse the stems thereon to the adjacent ends of the envelopes, said coils being separated by at least one station to permit reversal of the envelope thereat and insertion of a second stem in the head at said one station so that the said second stem is fused to the other end of the envelope at the second heating station.

4. Apparatus for sealing a stem to the end of an electric lamp envelope comprising a horizontal turret rotatably mounted on a vertical hollow column, a plurality of heads carried by said turret through a plurality of stations, each of said heads comprising support means mounted on said turret, a stem holder rigidly supported by said support means, and an envelope holder in vertical alignment with said stem holder and slidably mounted on said support means for vertical movement, means located at stations on opposite sides of said turret for effecting heating and sealing of a stem and adjacent envelope end in heads located at said opposed stations, and means for vertically moving the envelope holders of the opposite heads located at said opposed stations toward the co-operating stem holders to compress the seals between the stems and envelopes in said heads, said last-mentioned means comprising a horizontal cross arm extending diametrically across and above said turret between said opposite heads, the envelope holders on said heads being provided with engagement means engageable by the ends of said cross arm, a vertical shaft extending through the hollow column and carrying the said cross arm at its upper end, and means for reciprocating said shaft vertically to carry the cross arm to and from engagement with the engagement means of envelope holders on said opposite heads to actuate said holders.

5. In apparatus for sealing a stem to the end of an electric lamp envelope, a head comprising support means, a stem holder rigidly supported by said support means, and an envelope holder comprising separable jaws in vertical alignment with said stem holder and mounted to slide bodily on said support means in a vertical direction, a lat-

erally extending lever connected at one end to a portion of said envelope holder and mounted on a pin extending from said support means to pivot in a vertical plane, spring means normally tending to pivot said lever in a direction to hold said envelope holder in a raised position, means for fusing said stem and envelope together, actuating mechanism arranged to engage said lever and pivot it against the action of said spring means to lower the envelope holder and the envelope therein to compress the fused portions of the stem and envelope against the said stem holder, a ratchet carried by said support means adjacent to said lever, a spring-pressed pawl carried by said lever in a position to normally engage said ratchet and thereby retain the envelope holder in its lowered position against the action of said spring means on said lever, means for actuating said envelope holder jaws comprising a wedge member movable into and out of position between portions of said jaws, and release means comprising a bar member connected to said wedge member and terminating at a point adjacent to said pawl, said bar member being adapted to engage said pawl and release it from the ratchet upon movement of said wedge.

6. In apparatus of the class described comprising a horizontal turret rotatably mounted on a vertical hollow column, and a plurality of heads mounted on the periphery of said turret, each of said heads comprising support means and an envelope holder mounted for vertical movement on said support means, means for vertically moving envelope holders in heads located at diametrically opposed positions on said turret comprising a horizontal cross arm extending diametrically across and above said turret, said envelope holders being provided with engagement means engageable by the adjacent ends of said cross arm, a vertical shaft extending through said hollow column and carrying said cross arm, and means for moving said shaft vertically to carry the ends of said cross arm into engagement with the holder-engagement means and thereby effect vertical movement of said holders.

7. In apparatus of the class described, com-

prising a horizontal turret rotatably mounted on a vertical hollow column, and a plurality of heads mounted on the periphery of said turret, each of said heads comprising support means and an envelope holder mounted for vertical movement on said support means, means for vertically moving an envelope holder in a given head comprising a horizontal cross arm extending radially outward from the center of said turret to a position adjacent said head, said envelope holder being provided with engagement means engageable by the outer end of said cross arm, a vertical shaft extending through said hollow column and carrying said cross arm, and means for moving said shaft vertically to carry the outer end of said cross arm into engagement with the holder engagement means and thereby effect vertical movement of said holder.

8. In apparatus of the class described, comprising a horizontal turret rotatably mounted on a vertical hollow column, and a head mounted at the periphery of said turret, said head comprising support means, an envelope holder slidably mounted for vertical movement on said support means, means for moving said holder between two vertically spaced positions on said support means comprising a horizontal lever connected at one end to said holder and mounted on a portion of said support means for pivotal movement in a vertical plane and having a free end extending beyond the point where it is mounted on said support means, spring means urging said lever in a direction to maintain said holder in one of said two vertically spaced positions, and means for moving said holder to the other of said two positions comprising a horizontal cross arm extending radially outward from the center of said turret to a position adjacent the free end of said lever, a vertical shaft extending through said hollow column and carrying said cross arm, and means for moving said shaft vertically to carry the outer end of said cross arm into engagement with the said free end of said lever and thereby effect vertical movement of said holder.

ARTHUR J. WHITE.
ANTHONY J. MARSHAUS.
